UNITED STATES PATENT OFFICE.

THOMAS F. COSTELLO, OF MINNEAPOLIS, MINNESOTA.

AUTO VENTILATOR AND GLARESHIELD.

Application filed June 18, 1923. Serial No. 646,139.

This invention relates to a device adapted to be positioned in front of the transparent wind shield of an automobile, or to replace said wind shield and to form an anti-glare device for night driving or when driving against the sun. The device also has numerous other functions and advantages.

It is the object of this invention to provide a device such as a screen which can readily be seen through, which device is mounted on the supports for the ordinary wind shield and is movable to operative and inoperative position.

It is also an object of the invention to provide such a screen held in a frame which is frictionally movable in guides at each side of the wind shield, together with means for holding the screen in its upper position. These and other objects and advantages of the invention will be fully set forth in the following description made in connection with the accompanying drawings in which like reference characters refer to the same parts throughout the different views, and in which,

Fig. 1 is a view in side elevation of the device;

Fig. 2 is a view in vertical section through a portion of the device shown in Fig. 1; 30 Fig. 3 is a partial plan view of the device shown in Fig. 1, certain portions being broken away to clearly show the screen;

Fig. 4 is a view in side elevation of the screen used; and

Fig. 5 is a view of the device in front elevation, as seen at the right in Fig. 1.

Referring to the drawings, in Fig. 1 is shown in dotted lines the upper front portion of an automobile body carrying a wind shield of the standard type comprising a swinging upper portion *b* pivoted about an axis *c*. The side supports for the wind shield are indicated as *d*. Secured to the side supports *d* and extending rearwardly therefrom are vertically spaced straps or bars *1^a* which are secured to and support at their inner ends a vertically extending channel-shaped member *1*, it being understood that there are one of the members *1* at each side of the wind shield. The members *1*, as shown in Figs. 2 and 3, are channel shaped with the channels directed toward each other. A rectangular screen frame *6* is provided having formed therein a screen *5*, said frame having a central cross piece or base *7* therein. The screen *5* will be of such material and

mesh that it can readily be seen through and yet will prevent the passage of comparatively small insects. In practice, a screen of fine wire and of a size comprising twelve mesh per inch has been found very suitable. The screen frame *6* has at each side thereof springs *4* secured thereto, the springs *4* extending vertically along the sides of said frame with their intermediate portions secured thereto and have their end portions curved outwardly. The springs *4*, when the frame is disposed in the members *1*, bear against the front sides of said members, as shown in Figs. 2 and 3, so that the frame *6* is frictionally movable in the channel guide members *1*. The frame *6* also has rearwardly projecting portions *2* at its top edge which, when the screen is raised to its upper position, engage over the top of the members *1*, being pressed rearwardly by the springs *4*, the portions *2* thus forming catches for holding the frame and screen in its upper position. The guides *1* are connected at their bottom by a transverse base or tie piece *8*.

In operation, the members *1* will be held rigidly at each side of the wind shield. When it is desired to use the screen the frame *6* will be moved upwardly in the guide members *1* until the catches *2* engage over the top of the rear sides of the members *1*. The frame will be then held in its upper position and in substantial alinement with the top portion of the wind shield. The wind shield can either be left in its ordinary position or it can be swung downwardly about pivot *6* so that only the screen is in front of the driver. With such a screen device, the glare from approaching vehicles or from the sun will be efficiently dimmed. The screen is a non-reflector so that no objectionable reflections will be produced by a reflection of light from the screen. The air can readily pass through the screen and this will add more comfort to riding in hot or sultry weather. The screen also effectively prevents bugs or other insects reaching the driver's person or eyes. The screen can readily be dropped by merely pushing forwardly on the top thereof to disengage the catches *2* and allow the frame *6* to drop to the bottom of the guiding members *1* so that the screen will rest on the cross piece *8*. It is very easy to see through the screen and a good view of the road is thus afforded.

From the above description it is seen

that applicant has provided a simple and efficient device which can readily be attached to any standard automobile. The device can be quickly adjusted to suit various conditions and when in its lower inoperative position, is not in the way. The device has been amply demonstrated in actual practice and found to be very successful and efficient.

It will, of course, be understood that various changes may be made in the form, details, arrangement and proportions of the parts without departing from the scope of applicant's invention, which, generally stated, consists in a device capable of carrying out the objects above set forth and in the novel parts and combinations of parts disclosed and claimed and defined in the appended claims.

What is claimed is:

- 20 1. The combination with a wind shield of a vehicle having an upper and lower portion and spaced side supports, of a device comprising spaced guide members secured, re-

spectively, to each of said supports, a rigid screen-carrying frame vertically slidable in said guide members to be moved into and out of alinement, respectively, with the upper portion of said wind shield, means carried by said frame frictionally engaging said guides, and means for holding said frame and screen in position alined with said upper portion of said wind shield.

2. The combination with an automobile wind shield having spaced side supports, of a device comprising spaced vertical channel guide members secured, respectively, to said supports and having channels facing each other, a rectangular screen carrying frame slidable in said guide members, springs secured to the sides of said frame engaging said guide members, and a catch at each side of said frame at its upper end adapted to engage over the top of said guide members when said frame is in its upper position.

THOMAS F. COSTELLO.
